ELECTRIC VALVE TRANSLATING APPARATUS AND METHOD OF OPERATION

Albert H. Mittag and August Schmidt, Jr., Schenectady, N. Y., assignors to General Electric Company, a corporation of New York

Application June 16, 1943, Serial No. 490,996

5 Claims. (Cl. 315—266)

This invention relates to electric valve translating apparatus and more particularly to an improved method and apparatus for placing a plurality of parallel connected electric valve units in operation.

Electric valve systems employing a number of units operated in parallel have been widely used as a power supply for electrolytic processes requiring currents of large magnitudes. Some difficulty has been experienced in placing apparatus of this character in operation due to failure of all of the electric valves of the apparatus to become conductive at the intended time. The electric valves which conduct first temporarily assume all of the load which, in many cases, is sufficient to operate the protective equipment and isolate the overloaded unit or units. Some of the discrepancy in starting time among the various parallel units may be due to failure of the system provided for energizing the control members of the electric valves to render the electric valves conductive at sufficiently near the same instant. In installations employing electric valve means having starting electrodes of the make-alive type, at least a part of the discrepancy in starting time of the various units has been found to result from failure of the starting electrodes to form a cathode spot regularly for a considerable interval after the first energization thereof. In accordance with the teachings of this invention, there is provided an improved circuit and method of operating the same which insures a more uniform assumption of load by the various parallel operating units.

It is an object of this invention to provide new and improved electric valve translating apparatus.

It is another object of this invention to provide a new and improved control means for controlling the operation of a plurality of electric valve units in parallel and to provide an improved method of placing such apparatus in operation.

In accordance with the illustrated embodiment of this invention, a plurality of electric valve units are connected to operate in parallel between an alternating-current supply circuit and a direct-current load circuit. The electric valves are preferably of a type comprising a starting electrode of the make-alive type and a control member or grid which may be constructed as an anode baffle. In accordance with the invention, current impulses are first supplied to the starting electrodes to bring the starting electrodes to operating temperature. A negative bias is then impressed on the control members

or grids and all of the power circuit breakers interconnecting the supply and load circuits and the electric valve units are closed. After the starting electrodes have been energized for an interval of a minute or two to insure that they are at an operating temperature which insures reliable operation, the negative bias is removed from the control members of all of the electric valve units by means of a single switch which short circuits the source of negative bias through a current-limiting resistor. Relay means are provided for transferring the neutral connections of the excitation transformers associated with the control members of each of the valves from the common source of bias back to the respective cathode buses of the individual units. The short-circuiting switch may then be opened and the source of bias deenergized if desired to place the system in condition for another starting operation. With this apparatus and the method of operating it, the assumption of load by the individual units is sufficiently uniform to insure trouble free starting of the system.

This invention will be better understood by reference to the following description taken in connection with the accompanying drawing and its scope will be pointed out in the appended claims. In the drawing, the single figure illustrates schematically one embodiment of our invention.

In the arrangement shown in the drawing, a pair of electric valve rectifying units 10 and 11 are shown connected in parallel between a three-phase alternating-current supply circuit 12 and a direct-current load circuit comprising conductors 13 and 14. It will be understood that the present invention is particularly adapted for use in connection with a system employing a large number of rectifier units in parallel but, in order to simplify the drawing, only two of the units have been illustrated. The rectifier unit 10 comprises a supply transformer 15 having a delta-connected primary winding 16 and double-Y-connected secondary windings 17 and 18 having the neutrals thereof interconnected by an interphase transformer 19, the midpoint of which is connected to the direct-current line 13. Each of the phase terminals of the windings 17 and 18 are connected to a cathode bus 20 through the anode-cathode circuit of an electric valve means 21 and the contacts of a high-speed anode breaker illustrated schematically at 22. The electric valve means are preferably of the type employing an ionizable medium, such as a gas or vapor, and, as illustrated,

each includes an anode 23, a cathode, such as a pool of mercury 24, a make-alive type starting electrode 25, and a control member or grid 26. The cathode bus 20 of the rectifying unit 10 is connected to the direct-current line 14 through the contacts of a cathode breaker 27. The primary winding 16 of the supply transformer is connected with the alternating-current supply circuit through the contacts of the alternating-current circuit breaker 28. Electric valve rectifying unit 11 is in general the same as the electric valve rectifying unit 10 except that the voltages impressed on the anode-cathode circuits of the electric valves thereof are displaced in phase with respect to the voltages of the unit 10 by the supply transformer 29 which includes a Y-connected primary winding 30 and electrically displaced secondary windings 31 and 32. The remainder of the unit 11 is of the same arrangement as the unit 10 and the same reference numerals have been employed to designate corresponding parts. Only two electric valves have been illustrated in connection with the units 10 and 11 in order to simplify the drawing. It will be understood that a similar electric valve and circuit breaker interconnect each of the phase terminals of the transformer secondaries and the respective cathode buses 20.

In order to energize the starting electrodes 25 with periodic voltages of peaked wave form, there have been illustrated static impulsive circuits of the type described and claimed in the copending application of Alexanderson and Mittag, Serial No. 374,716, filed January 16, 1941, entitled "Electric control circuits," and assigned to the assignee of the present application. As illustrated, each of the excitation circuits 33 and 34 comprises a capacitance 35 which is arranged to be charged from one phase of an alternating-current excitation bus 36 through suitable phase-shifting means 37 and a charging impedance, such as a reactor 38. As illustrated, the bus 36 is energized directly from the supply circuit 12. The discharge circuit for the capacitance includes an auto-transformer 39 having a midtap connected with the cathode bus 20 and with the end terminals connected with the control electrodes 25 of electric valve means 21 associated with phase terminals of the supply transformer windings which are electrically displaced 180 electrical degrees. The circuit of each of the control electrodes preferably includes a unilaterally conducting device 40 to prevent reverse current from traversing the control electrode. The discharge of the capacitance through the autotransformer 39 and the control-electrode-to-cathode circuits of the electric valves 21 is controlled by a self-saturating reactor 41 connected in the discharge circuit of the capacitor 35. The reactor 41 is of the self-saturating type and the impedance thereof reduces abruptly at a predetermined point in the voltage wave impressed thereon by capacitor 35, thus producing symmetrical voltage peaks across the autotransformer 39 during both positive and negative half cycles. A unidirectional winding 42 may be provided and may be energized from a suitable source of direct current, not shown, to render the peaks symmetrical with respect to the positive and negative half cycles, if, for any reason, the instants of self-saturation are not exactly symmetrical.

In order to assist in the propagation of the arc from the cathode spot formed by the starting electrodes 25, there is provided means for impressing an alternating voltage on the control

members 26 having a suitable phase relation with respect to the alternating-current supply voltage. Associated with each of the units 10 and 11 is an excitation transformer 43 having a delta-connected primary winding 44 energized from the alternating-current supply circuit 12 through suitable phase-shifting means illustrated schematically at 45. The secondary winding 46 of the transformer 43 is preferably a diametric six-phase winding providing six phase terminals, one for each control member of each of the rectifier units. Only the control member of one of the electric valves of each unit is shown connected. The neutral of the transformer winding 46 is arranged to be connected with the cathode bus 20 of the rectifier unit 10 under the control of the contact 47 of an electromagnetic relay 48 or to the negative direct-current line 14 through the contact 50 of an electromagnetic relay 51, a current-limiting resistor 52 and a source of negative-biasing potential which may be impressed between the conductor 14 and a conductor 53. As illustrated in the drawing, the negative-biasing potential may be obtained from the alternating-current source by means of a rectifier circuit including a transformer 54 and a polyphase rectifier connection employing a plurality of rectifiers 55, preferably of the dry type. The output of the rectifier circuit is impressed across a capacitor 56 and the contacts 57 and 58 of a relay 59 through a resistor 60. In the closed position of the relay 59, the contacts 57 and 58 are connected with the conductors 53 and 14, respectively. The primary winding of the transformer 54 may be energized from the alternating-current supply circuit 12 through a three-pole electromagnetic switch 61 including an operating coil 62. As a source of energizing potential for relays 48, 51, 59, and coil 62, there is provided a single-phase auxiliary alternating-current circuit 63 which may be energized from any suitable source, such as supply circuit 12. The coil 62 and the coil 64 of the relay 59 are connected in parallel for energization from the circuit 63 under the control of a manual switch 65. Relays 48 and 51 are interlocked so that one is energized when the other is deenergized and vice versa. Referring particularly to the circuits of these relays associated with the rectifier unit 10, the operating coil 66 of relay 48 is connected across the single-phase circuit 63 through a normally closed contact 67 on the relay 51 and the operating coils 68 of relays 51 of units 10 and 11 are connected in parallel and across the alternating-current supply circuit 63 through the normally open contact 69 of a relay 70. The relay 70 is provided with an operating coil 71 which is energized from the circuit 63 through a transformer 72 with a manual switch 73.

The features and advantages which characterize the present invention will be better understood by a brief consideration of the operation of the system and particularly the method of placing the system in operation. First the alternating-current circuits 12 and 63 are energized by closure of the appropriate switches (not shown). When the circuit 12 is energized, the excitation circuits 33 and 34 are energized to transmit impulses of current to the starting electrodes 25 at the periodicity of the voltage of the alternating-current supply circuit and at a phase position with respect to the anode-cathode voltages dependent upon the setting of the phase-shifting means 37. Energization of the control circuit 63

energizes the relays 48 and connects the neutrals of the transformer secondary windings 46 directly with the cathode buses 20 of the respective units 10 and 11. Next the switch 73 is closed to pick up the relay 70 which, by closure of its contact 69, energizes the operating coils of the relays 51 associated with all of the rectifier units. Opening of the contacts 67 of the relays 51 deenergizes the operating coils 66 of the relay 48 to transfer the neutral connection of the respective transformer windings 46 from the individual cathode buses 20 to the common conductor 53. Next the switch 65 is closed to energize the operating windings of switch 61 and relay 59 to energize the bias rectifier circuit and to close the relay 59 to impress the output of the bias rectifier between the conductor 53 and the conductor 14. The conductor 53 is connected with the respective neutrals of the transformer windings 46 through resistors 52 and contacts 50 of relays 51 which are now in the closed position. The system is now ready for closure of the power breakers as soon as the starting electrodes 25 have been energized for a sufficient period to bring them to a good operating temperature. After closing all of the power breakers 22, 27, and 28 of all of the parallel units, the negative bias is removed simultaneously from the neutral connections of all of the transformer windings 46 by closing the single contact of a shorting switch 74 across the conductors 14 and 53. This removes the negative bias from all of the control members 26 at the same instant and, with the starting electrodes 25 all in operating condition, starting of all of the electric valves at the intended instant is assured. With the system now in operation, switch 73 is opened to deenergize relay 51 and energize relays 48 to transfer the neutral connections of the transformer windings 46 from the conductor 53 back to the respective buses 20 of the individual rectifier units. Switch 65 is opened to deenergize the bias source and switch 74 may be opened to place the system in readiness for another starting operation after a shutdown.

The system described above may be employed to place in operation a plurality of parallel connected electric valve units without the use of the single shorting switch. When used in this manner, the valve units are placed in operation by opening the switch 73 to deenergize relays 51 and energize relays 48 to transfer the neutral connections of the excitation transformer windings 46 from the conductor 53 to the cathode buses 20. However, in the operation of the system in this manner, the removal of the negative bias is accomplished by the dropout of a plurality of relays which may not in all cases occur with the degree of simultaneity required for satisfactory pickup of the load current by the parallel units.

From the foregoing description, it is apparent that the present invention provides a system and method for placing a plurality of parallel electric valve units in operation and in which discrepancies in the starting of the individual electric valves due to failure of the electrodes to form a cathode spot during the first cycles that they are energized or by failure of the control member excitation system to release the electric valves at the same instant are eliminated.

While there has been shown and described a particular embodiment of this invention, it will be obvious to those skilled in the art that changes and modifications may be made without departing from this invention in its broader aspects and it is, therefore, aimed in the appended claims to

cover all such changes and modifications as fall within the true spirit and scope of this invention.

What we claim as new and desire to secure by Letters Patent of the United States, is:

1. In combination, an alternating-current circuit, a direct-current circuit, a plurality of groups of electric valve means connected between said circuits, each of said valve means comprising an anode, a pool-type cathode, a make-alive starting electrode, and a control member interposed between said anode and said cathode, means connecting the cathodes of said electric valve means to one side of said direct-current circuit, excitation circuits for supplying electrical impulses to said starting electrodes at the periodicity of said alternating-current circuit to form periodically cathode spots, a plurality of excitation transformers arranged one with each of said groups of electric valve means and each having a winding including phase terminals connected with the control members of its associated group of electric valve means for impressing an alternating voltage thereon and a neutral terminal, a conductor common to the neutral terminals of all of said excitation transformers, means including a source of unidirectional voltage for impressing between said conductor and all of said cathodes a unidirectional voltage with said conductor having a negative polarity, means connecting the neutral terminal of each of said transformer windings and said conductor to impress a negative bias voltage on said control members to maintain said valve means nonconductive while said starting electrodes are energized, and a single switching means for short circuiting the cathodes of said electric valve means to said conductor to remove said unidirectional voltage simultaneously from all of said control members.
2. In combination, an alternating-current circuit, a direct-current circuit, a plurality of groups of electric valve means connected between said circuits, each of said valve means comprising an anode, a pool-type cathode, a make-alive starting electrode, and a control member interposed between said anode and said cathode, means connecting the cathodes of said electric valve means to one side of said direct-current circuit, excitation circuits for supplying electrical impulses to said starting electrodes at the periodicity of said alternating-current circuit to form periodically cathode spots, an excitation transformer associated with each of said groups of electric valve means and having a winding including phase terminals connected with said control members for impressing alternating voltages thereon and a neutral terminal, means including switching means connecting the neutral terminal of each of said transformer windings with the cathodes of the associated group of electric valve means, a conductor, means for impressing between said conductor and all of said cathodes a unidirectional voltage with said conductor having a negative polarity, switching means connected between the neutral terminal of each of said transformer windings and said conductor so that when said first-mentioned switching means are in an open position and said last-mentioned switching means are in a closed position a negative bias voltage is impressed on said control members to maintain said valve means nonconductive, means for short circuiting the cathodes of said electric valve means to said conductor to remove said unidirectional voltage from all of said control members simultaneously.

ously, and means for opening said last-mentioned switching means and closing said first-mentioned switching means to exclude said conductor from the circuit of the control members.

3. In combination, an alternating-current circuit, a direct-current circuit, a plurality of groups of electric valve means connected between said circuits, each of said valve means comprising an anode, a cathode, and a control member interposed between said anode and said cathode, means for establishing electron emission from each of said cathodes periodically in each positive anode cycle of its associated anode, means connecting the cathodes of said electric valve means to one side of said direct-current circuit, a plurality of excitation transformers arranged one with each of said groups of electric valve means and each having a winding including phase terminals connected with the control members of its associated valve group for impressing an alternating voltage thereon and a neutral terminal, a conductor common to the neutral terminals of all of said excitation transformers, means including a source of unidirectional voltage for impressing between said conductor and all of said cathodes a unidirectional voltage with said conductor having a negative polarity, separate means associated with each neutral terminal for interconnecting the neutral terminal of each of said transformer windings and said conductor to impress a negative bias voltage on said control members to maintain said valve means nonconductive during an initial period of time sufficient to establish periodic electron emission from the cathodes of all of said valve groups, and a single switching means for interconnecting all the cathodes of said electric valve means and said conductor thereby to by-pass and to remove said unidirectional voltage simultaneously from all of said control members after periodic cathode emission has been established for said initial period.

4. In combination, an alternating-current circuit, a direct-current circuit, a plurality of groups of electric valve means connected between said circuits, each of said valve means comprising an anode, a cathode, and a control member interposed between said anode and said cathode, means for establishing electron emission from each of said cathodes periodically in each positive anode cycle of its associated anode, means connecting the cathodes of said electric valve means to one side of said direct-current circuit, a plurality of excitation transformers arranged one with each of said groups of electric valve means and each having a winding including phase terminals connected with said con-

trol members for impressing alternating voltages thereon and a neutral terminal, means including separate switching means associated with each neutral terminal for connecting its associated neutral terminal to the cathodes of the associated group of electric valve means, a conductor common to all of said neutral terminals, means including a single source of unidirectional voltage for impressing between said conductor and all of said cathodes a unidirectional voltage with said conductor having a negative polarity, a separate additional switching means connected between the neutral terminal of each of said transformer windings and said conductor so that when said first-mentioned switching means are in an open position and said last-mentioned switching means are in a closed position a negative bias voltage is impressed on said control members to maintain said valve means nonconductive, while all of said cathodes are in an emissive condition and for a period of time after initiation of said emission and means for opening said last-mentioned switching means and closing said first-mentioned switching means to exclude said conductor from the circuit of the control members to render said valve means conductive at the termination of said period of time.

5. In combination, an alternating current circuit, a direct current circuit, a plurality of groups of electric valves, switching means having open and closed positions for controlling the connection of said plurality of groups of electric valves in parallel relation between said alternating and direct current circuits, each of said valves comprising an anode, a pool-type cathode, a make-alive starting electrode, and a control member interposed between said anode and said cathode, a source of negative bias potential, a source of alternating control potential, means for connecting said sources of potential in superposed relation between each control member and its associated cathode, said negative bias potential being of a value sufficient to maintain each valve non-conductive when said switching means is in a closed position and each valve is in a state of ionization for conduction, means for energizing each starting electrode with periodic impulses of current to form a cathode spot on its associated cathode, and single switching means for short circuiting said negative bias potential to remove simultaneously the negative bias potential from all said control members to render said valve means conductive after said starting electrodes have been energized a predetermined time.

AUGUST SCHMIDT, JR.
